UNITED STATES PATENT OFFICE

EDWIN F. BRITTON, JR., OF MAPLEWOOD, NEW JERSEY, ASSIGNOR, BY MESNE ASSIGNMENTS, TO MONROE CALCULATING MACHINE COMPANY, OF ORANGE, NEW JERSEY, A CORPORATION OF DELAWARE

ZERO-KEY MECHANISM FOR KEY-SET REGISTERS

Application filed September 22, 1925. Serial No. 57,868.

The invention has relation to zero key mechanism for key-set registers, such for instance as the calculating machine disclosed in the Monroe Patent 1,306,606; the Britten Patent 1,474,230, and the Phinney Patent 1,432,616. While this invention is shown as applied to the Monroe calculating machine, its use is not confined to this reversible cycle type, as it may be adapted to any machine 10 having keys which may be set for repeat operations.

It has been customary in such machines to provide a column lock which will lock any key, from 1 to 9, in a key column in a depressed position. Usually a column correction key has been provided at the bottom of the column which if depressed will release the column lock, for restoration of any depressed key of the column to normal position.

20 In machines of this type it has been customary to provide repeat and non-repeat key mechanism similar to that shown in said Monroe and Phinney patents, which for non-repeat operations operates in such a manner that if an item is set up in the keyboard and the machine is operated once, as in addition or subtraction, all of the column locks will be released and the 1 to 9 keys simultaneously automatically restored to their normal elevated position. For purpose of 30 making multiplication and division calculations, however, it is desirable to operate the machine several times without changing the key setting, and therefore the repeat key mechanism provides that the column locks will remain undisturbed and depressed keys of the keyboard will remain depressed through any number of cycles of operation, until suitable releasing mechanism is manually operated for return of depressed keys to 40 normal position.

In performing additions and subtractions by the non-repeat method there has been the objection that as soon as the key value has 45 been registered the keys are returned to normal position, and the key value being added into and merged with the previous numeral wheel reading, the operator had no means of checking back to determine whether or not the correct keys had been depressed. If,

however, additions and subtractions are performed by the repeat method, the keys which have been depressed remain depressed after the registration has been made, and the operator may, by glancing at them, determine 55 whether or not the correct key value has been registered. If an error has been made, a reverse rotation of the operating crank (or the equivalent manipulation) will cancel the registration, after which the keyboard setting 60 may be corrected and the correct value registered. This method of operation with the repeat key set has been brought into quite general use within recent years, and has been termed "locked figure addition". By using 65 this system it is possible to perform additions, subtractions, multiplications and divisions without setting for repeat or non-repeat operation.

An object of the present invention is to 70 provide mechanism whereby the operation of locked figure addition may be accomplished by an improved method. Other objects and advantages will hereafter appear.

The invention consists in the novel construction and combinations of parts, as set forth in the appended claims.

In the accompanying drawings, illustrating an embodiment of the invention:

Figure 1 is a plan view of a calculating machine to which the invention is shown as applied.

Figure 2 is a section, taken on the line 2—2, Figure 1.

Figure 2^a is a detail face view of a "1" key; 85 cooperating parts appearing in section.

Figure 3 is a detail front view of a portion of the keyboard, with parts of the casing removed and parts in section, the keys being in normal position, with different keys depressed in two adjacent columns.

Figure 4 is a detail front view of the clear and one of the zero keys and associated parts, with the clear key in depressed position, assumed during operation thereof.

Figure 5 is a side view of the same.

Figure 6 is a detail side view of the repeat and non-repeat mechanism, with the non-repeat key depressed.

Figure 7 is a detail face view of the non-repeat key.

Figure 8 is a detail plan view of the mechanism of Figure 6, but with the parts positioned by the depression of the repeat key.

The keyboard

In these drawings the keys representing the digits 1 to 9 are designated by the numeral 1. After keys have been set in one or more columns, representing values which are to be registered, the operating crank 3 is rotated once forwardly if it is desired to add the key value, and once reversely in subtracting. The rotation of the operating crank causes the key values to be registered upon the register wheels 13, which will accumulate the total. The carriage 2 in which register wheels 13 are mounted may be shifted transversely by use of the knob 16, in order that key values may be registered in the higher or lower value register wheels as required. Counting wheels 17 are provided which will register the number of forward or reverse rotations of the operating crank 3, thereby registering the multiplier in multiplication or the quotient in division. The register wheels and the counting wheels may be restored to zero by operation of the zeroizing crank 7. The constructional details providing these general operative features are well known in the art and form no part of the present invention.

In carrying out the present invention the column correction keys become zero keys (one zero key for each denominational column), and are so marked upon the heads thereof, similar to the marking of the other keys.

Each column of keys of the machine is provided with a key locking bar 4, shown in Figures 2 to 4. This bar is pivoted at its ends upon pins 5 and is actuated by spring 6 to engage with notches of the key stems, each digital key stem having upper and lower notches 11 and 8 (see Fig. 2^a). The lock bar normally engages the lower notches of the key stems, and engages the upper notches of said stems to hold the keys in set position, the lower notches having each a cam edge 10 acting in the depression of any key to cam the lock bar outwardly to release any other depressed key of the related column, each key having a return spring 9, all as stated in detail in said patents.

55 The zero key of each denominational column is provided with upper and lower notches 23 and 24, (see Figs. 3 and 4), and is adapted to be locked in a partially depressed position by the aforesaid lock bar 4 of the related column engaging the upper notch 23 thereof. For reasons which will be explained each notch may be provided with a cam upper edge 25, so that the lock bar 4 will be cammed outwardly to release position twice during the complete depression of a zero key. The

upper notch 23 is engaged by lock bar 4 to hold the zero key in partially depressed position, as in Figure 3, while the lower notch 24 has the same office precisely as the lower notch 8 of keys 1.

It is thus apparent that if an operator depresses a zero key, any other key in the related column will be released and restored to normal position, and the zero key will be held partially depressed, with the lock bar 4 engaging the upper notch thereof, but capable of downward movement to completely depressed position shown in Figures 4 and 5. On the other hand if a higher key is depressed the zero key will be released and restored to normal position and the said higher key held depressed. The zero keys are provided with stops 26 to limit their upward movement.

Means are provided whereby a partial or full depression of the clear key 22 will selectively depress the released zero keys to locking position, or will completely depress all of the zero keys simultaneously to the full extent of their strokes. This means consists of universal bar 27 having an upper flange 28 under which engage the lower lugs 32 of the zero keys, each zero key having its lower end bent to form such lug, and said universal bar having an end extension 33 engaged by a shoulder 36 of said clear key. Spring means are provided to normally hold universal bar 27 and clear key 22 in elevated position. In this way all depressed keys of the keyboard higher than the zero keys will be released and restored to normal raised position, and all of the zero keys will be held in partially depressed position following release of the clear key.

It is desirable, if by improper operation a zero key and any higher key 1 to 9 should be both locked down simultaneously by lock bar 4, that depression of the said zero key or of the clear key shall operate said lock bar and release said higher key 1 to 9, and that the zero key shall be held in partially depressed position, and it is for this reason that the upper notch 23 of the zero key may be provided with the upper cam edge 25, acting in the movement of the zero key from partially depressed to completely depressed position to move said lock bar outwardly to release position. Upon release of the zero key from completely depressed position it will be restored to partially depressed position by its return spring, whereupon the lock bar 4 will engage notch 23 to hold the key partially depressed. This extra movement of the zero key from partially depressed to fully depressed position therefore admits of the restoration to normal raised position of any higher depressed key in the column even though the zero key is already depressed and so held.

When the clear key is fully depressed the zero keys are all simultaneously depressed a greater distance than in previous machines, so that when the zero keys are released and restored to partially depressed position and so held by engagement of the lock bars with the upper key notches 23, the zero keys will still be depressed sufficiently below normal to render their depression apparent to the operator.

Selective clearing operations

Should no erroneous setting of a zero and a 1 to 9 key be present, a partial depression of the clear key will be sufficient to clear the keyboard. By this method of operation, the lock bars in columns wherein no key 1 to 9 is in depressed position, and the zero keys in such columns, need be operated only sufficiently to provide for clearance between the walls of notches 23 of the zero keys being depressed and the corresponding lock bars 4. Thus the clear key will be relieved of the load encountered in moving the lock bars and zero keys in columns needing no clearing.

The zero and clear key combination disclosed herein also provides for the "splitting" of the keyboard between any columns desired, so that keys in the selected columns may be rendered irresponsible to release by an operative movement of the clear key.

In columns wherein permanent setting is desired, a value key is depressed while the zero key is held with notch 23 thereof opposite bail 4. Preferably, all the zero keys are held in this position by means of the clear key, while value keys in the selected columns are being set. Upon release of the zero keys, they will remain depressed, notwithstanding that value keys are also held down in the same columns. Selective operation of the clear key, as above explained, will not release value keys set in this manner, since the zero keys are already depressed, while it will, of course, release all value keys set in the usual way.

When it is desired to clear the entire keyboard, the zero keys may be individually or selectively depressed to the full extent of their stroke; other value keys may be depressed, or other clearing means employed.

In the construction illustrated herein, the above described selective clearing operations are facilitated by the added spring tension encountered by the clear key after the zero keys have been depressed to locking position, since a light manual stroke may readily be checked at this point.

All of the above operations relate to "locked figure addition", the method of operation above mentioned.

Although termed "locked figure addition", the system is generally used also for subtraction, and corresponds to the system used for multiplication and division calculations.

Repeat and non-repeat key mechanism

In this invention the functioning of the clear key is entirely independent of the mechanism for restoring the depressed keys of all columns to normal position at the end of the stroke of the operating crank, said mechanism including the repeat and non-repeat keys and being used only optionally, since it is not essential to the performance of any mathematical calculation. It may further be used to clear the entire keyboard, if certain value keys have been rendered irresponsible to release by an operative movement of the clear key.

The repeat and non-repeat key mechanism of the said Phinney Patent 1,432,616, has been modified somewhat to provide for its proper operation in conjunction with the clear key and zero key mechanism of this machine. Figures 6, 7 and 8 show these modifications sufficiently.

The operating crank 3 is secured to driving gear 19, carrying pin 29 (Figs. 6 and 8). Cam 18 is loosely mounted on the same axis as gear 19, and is driven by pin 29, there being lost motion of said pin between the opposite sides of the cam as the direction of rotation of crank 3 is reversed, thereby causing the cam to lag and to function at the proper time, in either direction of rotation. Cam 18 operates lever 14, fulcrumed at 15 and having its movement limited by stop 37, working in slot 39 of said lever. Bell lever 21, fulcrumed at 40 (see Fig. 8), is engaged by lever 14 and engages slide 12, to thereby operate rock bars 4 (see Fig. 3) and release all keys of the keyboard, from 0 to 9. Slide 12 is operated only for non-repeat registrations.

The character of the operation is selectively controlled by moving the lever 14 into or out of the path of cam 18, the lever 14 being slidable transversely of its plane with its fulcrum stud 15 and slidably adjusted by operation of key 20, which has a cam slot 30 engaged by the tail arm 35 of said lever, the cam edges of said slot causing the shifting of lever 14 toward the right or the left for non-repeat or repeat operations whenever key 20 is depressed or raised. Key 20 being depressed, the upper end of cam slot 30 will hold lever 14 in its operative position, as shifted to the right, and said key being raised, as in Figure 8, the lower end of said cam slot will hold lever 14 in its inoperative position, as shifted to the left.

Walking beam lever 34 is fulcrumed on stud 41 and engages at one end a slot in key 20 and at its other end a similar slot in a key 31, working in conjunction with key 20. Spring pawl 38 serves to releasably hold lever 34 in either position taken in the operation of key 20 or key 31, and lever 34 connects said keys so that either one or the other key will

be depressed at all times, and the depression of one key will cause the other key to rise. Thus when key 31 is depressed, repeated rotations of operating crank 3 may be made 5 without releasing any of the keys 0 to 9 of the keyboard, but when key 20 is depressed, all depressed keys of the keyboard will be released and will be restored to normal position whenever operating crank 3 is rotated once 10 in either direction. This repeat and non-repeat key mechanism is the same as that of said Phinney patent, except that the lever 14 is now independent of the clear key, instead of being operated thereby.

15

Operation

When the mechanism is set for non-repeat operations the action of the machine is the same as in said Phinney patent, excepting 20 that if a zero key is depressed to make a correction it will so remain until the operating crank 3 is rotated once or until another key in the same column is depressed; and if the clear key 22 is depressed to make the correction, all zero keys will be depressed and 25 locked in partially depressed position.

When the machine is operated by the repeat key method, with repeat key 31 depressed, the clear key 22 is the only means 30 for releasing all of the keys 1 to 9 inclusive of the keyboard, and upon operation of the clear key the zero keys will be or will remain depressed. If any key from 0 to 9 of a given 35 column is depressed it will release any other key or keys of the column which has been depressed, and the new key setting will remain through any number of cycles of operation of the operating crank 3, until altered by depression of another key of the same 40 column or of the clear key.

With this method of operation, one key in every column will be depressed at all times, this enabling an operator to determine by 45 glancing at the zero keys whether or not values from 1 to 9 are set up in any column, without looking at all of the keys of the columns.

It frequently occurs that successive key 50 settings involved repeated depression of a key in certain columns and not in others. For example, one item to be registered may be \$44.25 and the next item \$44.75, in which case the operator needs merely depress the 70¢ key, in place of the previously depressed 55 20¢ key. In this example the operation of three keys is avoided through the use of the "locked figure addition" system. On the other hand, by this system it becomes necessary to depress zero keys or the clear key 60 in order to obtain a proper key setting under certain conditions. For example, if \$5.55 has been added, and the next item is \$5.00, the 55¢ keys should be released by depressing the zero keys of these columns. Through using 65 the "locked figure addition" system, the op-

eration of the repeat and non-repeat keys as the operator changes from multiplication to addition, or from one calculation to another of opposite nature, may be eliminated. This again has a tendency to simplify the work, 70 and prevents error through failure to properly set the machine before starting a calculation, only to find after some work has been done that the machine was improperly set and the operation must be started over again. 75 In some cases it is preferable for the operator to strike the clear key between items added and make an entirely new keyboard setting, and in other cases it would be easier to revise the old setting by depressing the 80 proper zero and 1 to 9 keys.

Through the use of this "locked figure addition" system, which it is an object of the present invention to perfect, any registration 85 which has been made is retained in the keyboard, so that it may be checked, when, if an error appears, a reverse rotation of the operating crank will restore the registration as it was before the error was made, whereupon the keyboard setting may be corrected and the 90 proper registration made. This mode of operation has been found to have a very practical advantage and has the net result of attaining more accuracy and speed in the 95 operation of the machine.

The utility of the split keyboard involves 100 series of operations containing both variable and constant factors, and may be illustrated by an example involving a constant divisor. Heretofore, after the first division had been accomplished, the divisor was cleared from the keyboard, so that a new dividend could be set up and transferred to the numeral wheels.

By the use of the present invention, the operation in dividing 4276 and 5478 by 1728 105 (as an example which may be supposed to be extended indefinitely by the inclusion of other dividends) would be accomplished as follows:

With the carriage 2 shifted to the extreme left and with the zero keys held in their locked-down position, set up the divisor, 1728, at the right of the keyboard. Set up 110 the first dividend, 4276, at the left of the keyboard, in the usual way, without holding the zero keys. Rotate the crank 3 forwardly for one turn, whereupon the dividend and the divisor will appear upon the numeral wheels 13 and the numeral "1" upon the wheels 17. 115 The clear key is now partially depressed, thereby clearing the dividend 4267 from the keyboard but leaving the divisor 1728 set up. Rotate the crank 3 reversely for one turn, to remove the number "1" from the wheel 17; 120 this operation also removing the divisor from the wheels 13. Shift the carriage to the right until the dividend in wheels 13 is directly over the divisor on the keyboard, and operate the crank 3 and carriage shifting knob 16, to 125 130

accomplish the division in the well-known manner. At the completion of the operation, the wheels 17 will read 2.4745. Clear the numeral wheels 18 and 17. Set the second dividend 5478 at the left of the keyboard in the usual way; rotate the crank 3 forwardly, partially depress the clear key; rotate the crank reversely; shift the carriage 2 to its proper position, and divide as before, whereupon the wheels 17 will read 3.1701.

10 I claim:

1. Selecting mechanism for key-set calculating machines, including a plurality of columns of digital value and zero keys, holding means for each column, said keys being each adapted when depressed to be so held by the related holding means and each further adapted upon depression to move the related holding means and release any set key of the same column, and means including a member common to the zero keys for depressing all zero keys.

2. Selecting mechanism for key-set calculating machines, including a plurality of columns of digital value and other keys, a holding member common to each column, said keys being each adapted when depressed to be so held by the related member and each further adapted upon depression to move the related member and release any set key of the same column, said other keys being each when set further movable and adapted thereupon to move the related member and release any set digital key of the same column.

35 3. Selecting mechanism for key-set calculating machines, including a plurality of columns of digital value keys, a holding member for each column, said keys being each adapted when depressed to be so held by the related holding member and each further adapted upon depression to move the related holding member and release any set key of the same column, and clearing means including a member manually operable to select and move the holding members of columns wherein digital value keys are set and to release said keys.

4. In a key-set calculating machine having a plurality of banks of depressible value keys, and means for holding the keys of each bank in depressed position; universal clearing means operative to release the depressed keys from their holding means and including a clear key and means selectively manipulable to render the depressed value keys in any of said banks irresponsive to an operative movement of said clear key.

5. In a key-set calculating machine having a plurality of banks of depressible value keys, and means for holding the keys of each bank in depressed position; universal clearing means operative to release the depressed keys from their holding means and including a clear key and keys individual to the banks and depressible simultaneously with value

keys in the same banks to render the latter keys irresponsive to an operative movement of said clear key.

6. In a key-set calculating machine having a plurality of banks of depressible value keys, and means for holding the keys of each bank in depressed position; universal clearing means including a member operable to release the depressed keys in any selected portion of the keyboard, and a second universal clearing means operable invariably to clear the entire keyboard.

7. In a key-set calculating machine having a plurality of banks of depressible value keys, and means for holding the keys of each bank in depressed position; universal clearing means including a member operable to release the depressed keys in any selected portion of the keyboard and including keys individual to the banks and operable at any time to release the keys in the same banks.

In testimony whereof I affix my signature,
EDWIN F. BRITTON, JR.
